UNITED STATES PATENT OFFICE

153,800

DESIGN FOR AN EAR CLIP FINDING

Karl F. Hoecke, Newark, N. J., assignor to Eastern Jewelry Finding Works, Inc., a corporation of New Jersey

Application February 18, 1948, Serial No. 144,567

Term of patent 14 years

(Cl. D45—9)

To all whom it may concern:

Be it known that I, Karl F. Hoecke, a citizen of the United States, residing at Newark, in the county of Essex and State of New Jersey, have invented a new, original, and ornamental Design for Ear Clip Finding, of which the following is a specification, reference being had to the accompanying drawing, constituting a part thereof.

Fig. 1 is a front view of an ear clip finding, showing my novel design;

Fig. 2 is a side view; and

Fig. 3 is a rear view thereof.

I claim:

The ornamental design for an ear clip finding, substantially as shown.

KARL F. HOECKELE.
